Application December 17, 1931, Serial No. 581,579

3 Claims. (Cl. 103—118)

This invention relates to a pump construction particularly adaptable to and for the pumping of gasoline and other liquids to be dispensed.

There are various types of so-called pedestal pumps for the dispensing of gasoline and motor fuels which are arranged to have mounted therein the pump mechanism. The pump mechanism may be manually or power operable. When power operable, the pump is usually electric motor driven.

One object of the present invention is to construct the pump assembly so that it may be universally adapted for mounting in and upon various types of pedestal pumps and other supports.

A second object of the invention is to combine in one pump assembly provision for motor driving the pump and for manually operating the same.

Another object of the invention is to so arrange the pump assembly whereby the respective parts thereof may be readily detached one from the other for removal of parts requiring replacement, repair or adjustment.

Another object of the invention is to provide a filter or screen construction for a pump which, in addition to automatically separating water, dirt and other matter from the liquid being pumped, collects the filtrate and which when the filter or screen is removed, simultaneously removes the separated filtrate from the pumping system.

The chief feature of the invention consists in the construction of the various parts and the association thereof, whereby the foregoing objects are accomplished.

Another feature of the invention consists in the belt tensioning construction which can be readily manipulated without belt removal.

The full nature of the invention will be understood from the accompanying drawings and the following description and claims:—

In the drawings, Fig. 1 is a side elevation of a motor driven pump assembly embodying the invention, the assembly being arranged for side wall mounting.

Fig. 2 is an end elevation thereof.

Fig. 3 is a view similar to Figure 2 but on a smaller scale and of a modified type of support and mounting.

Fig. 4 is a side elevation of a modified form of construction illustrating the manual pump operation, parts being shown in central section for illustrating the same and other parts in detail. This figure illustrates the central section, the pump rotor and housing.

Fig. 5 is a transverse sectional view through the pump assembly discharge mechanism and illustrates in detail the screen and filter and relief valve constructions and mounting.

Fig. 6 is an end elevational view of a modified form of mounting, the driving mechanism being omitted.

In Figs. 1 and 2 of the drawings, 10 indicates a relief valve and filter and screen housing which includes at one side the anchoring or supporting bracket portion 11, whereby through bolts, nuts or the like, inserted in the openings 12, the pump assembly may be suitably mounted and supported. The housing 10 includes a plurality of upwardly directed bosses 13 adapted to detachably support by means 14 a motor unit, indicated generally by the numeral 15, the shaft 16 of which mounts a V-shaped driving pulley 17. The lower face 18 of the housing 10 is adapted to abuttingly support a rotor housing 19 which is arranged—see Fig. 4—to provide a pump or rotor chamber 20 therein, having an open face 21 and an aligned bearing portion 22. Mounted in the chamber is a pump rotor, indicated generally by the numeral 23, and the same is mounted upon the shaft 24 rotatably supported at one end in bearing portion 22 of rotor housing 19.

The rotor chamber 20 is closed by a cover or cap 25 secured to the same as at 26, and said cover or cap terminates in an extended bearing 27 arranged to receive a sealing construction, indicated generally by the numeral 28, and retained in operative relation by the cap 29. This sealing construction is illustrated, described and claimed in a co-pending prior application.

The elongated bearing supports the rotor shaft 24 and seals the pump. The extended end of said shaft terminates in a shoulder 30 against which abuts the hub 31. This hub is elongated and threaded as at 32. The hub is retained upon the shaft by the nut 33 and is prevented from rotating thereon by the key construction 34, or any other equivalent structure. Projecting radially from the hub 31 are the spider arms 35 that support a rim 36, said rim including an inwardly tapered face frusto conical in form, as at 37. Each of the spider arms 35 is provided with an aperture 38 and said apertures are equidistant from the axis and are of like size.

Threadedly mounted on the hub 31 is a supplementary hub 39 from which radially extends a plurality of spider arms 40 that terminate in a peripheral rim 41 inwardly and frusto conically tapered as at 42.

The resultant construction is a V-pulley, the

effective diameter of which is obtained by axial adjustment of the two pulley forming plates. To maintain the plates in predetermined spaced relation, one of the arms 40 includes a threaded aperture 43 that receives a locking plug in the form of a threaded bolt 44, terminating in a pin 45 that is receivable by any one of the openings 38 in the arms 35. The adjustable pulley construction, as shown clearly in Fig. 1, is arranged 10 for belt alignment with respect to the driving pulley 17 on the motor and when the belt 46 suitably connects the same with the desired tension in the belt, the motor will properly drive the rotor 23 for pumping of the liquid supplied to the housing 10 by the intake pipe indicated by the dotted lines in Fig. 1 and by the numeral 47.

Pipe 47 communicates with the intake 48 in chamber 49 in the housing 10. Chamber 49 communicates with chamber 50 through an apertured 20 partition 51 having the aperture 52 therein. A well 53 communicates with portion 54—see Fig. 1—of the pump rotor housing 19 and the pump discharge from the rotor housing communicates with the inlet 55 of chamber 56, having the discharge 57 to which the discharge pipe or conduit of the unit is connected. Chamber 56 has an opening 58 therein which supports a relief valve structure indicated generally by the numeral 59. The relief valve discharges into chamber 60 that 30 is in free communication with the chamber 50. The pressure at which the relief valve will open is adjusted by the mechanism indicated at 61, the same being protected by a cap or closure 62, the housing 10 including an aperture 63 in alignment 35 with the aperture 58 whereby the entire relief valve structure, if and when desired, may be readily removed through opening 63 for cleaning, repair or replacement. When cap 62 is removed the relief valve may be adjusted.

40 The chamber 50 in axial alignment with the aperture 52 includes a seat or recess 64 defined by the bearing face 65. A screen structure including a frame work terminates in an extension 66, receivable by the recess 64 and an end closure 67 that bears against the face 65. The screen structure is of tubular character and includes the screening 68, suitably braced or supported and protected at 69 and 70 and includes an opposite open end defined by a peripheral portion 71 that closely engages the wall of aperture 52 and forms a tight sealing bearing for the opposite end of the screen. Extending from the screen and into the chamber 49, is a ported intake extension arrangement 72 that terminates 55 in a cap 73 apertured as at 74 and slidably supported upon a bolt 75, threadedly mounted in a closure 76, threadedly mounted in the aperture 77, said aperture being in alignment with the aperture 52 and the recess 64. Interposed between the closure 76 and the cap 73 is a coil spring 78. When the cap or closure 76 is removed from opening 77, the screen passes through the partition aperture and through opening 77. When it is removed, it carries with it all of the collected debris separated from the liquid that has been supplied through the intake 48 to the pump.

70 The pump which takes the screened liquid from chamber 50 forces it into chamber 56 and out through the discharge 57. If the pressure increases beyond that for which the relief valve is set, the excess liquid is bypassed into chamber 60 and immediately is recirculated by the pump without passing through the screen nor returning to the chamber 49. In other words, the liq-

uid only passes once through the screen even though recirculated.

Whenever manual operation is desired or required, the belt 46, if a motor is provided with the structure, is removed and there is threadedly mounted upon threaded hub 31—see Fig. 4—80 a pinion 80. As shown clearly in Figs. 4 and 5, the closure or cap 76 is extended as at 81 and the same is adapted to receive a hub 82 suitably secured as at 83 thereto. Said hub includes a plate gear 84 that meshes with the pinion 80. The hub 82 includes the aligned radial notches 85 adapted to seat the pin 86 carried by portion 87 of the crank having the handle 88. The locking end 89 is receivable by the recess 90 in the extension 81 of the cap or closure 76. Rotation of the hand crank, therefore, will rotate the rotor shaft 24 and manual operation is thus obtained.

90 In Fig. 3 a different type of support from that shown in Figs. 1 and 2 is illustrated and herein the supporting structure includes a pair of spaced side members 91 and detachably supported therebetween, as at 92, is a plate 93. Said plate is suitably apertured and the bolts 14 shown in 95 Figs. 1 and 2 not only secure the motor to the housing 10, but also securing the housing 10 to the transverse member 93.

100 In Fig. 6 a modified form of support is illustrated wherein the housing 110 includes lateral faces to which are detachably secured as at 112 upon opposite sides, the outwardly directed supporting flanges 111. These in turn are suitably supported upon adjacent sides of a pair of supports.

110 The resulting construction, therefore, is one that is universally adaptable for various types of mountings and which is universally adaptable for operation in that it may be power operable or manually operable. Furthermore, it will 115 be readily apparent that the relief valve structure and the filter or screen may be readily removed without detaching any of the assembled parts other than the closures, and that the rotor or the motor may be detached from the housing 120 10 for repair or replacement.

The invention claimed is:

1. A pump assembly including a rotor housing, an apertured detachable cover therefor, a pump shaft extending through the cover aperture and 125 having an end terminating and seatable in the housing, a unitary filter and relief valve housing arranged to communicate with the rotor housing when assembled, means on the extended end of said shaft for rotating the same, means detachably securing the housings together, a pair of closures for the second mentioned housing, a relief valve structure detachably mounted in the second mentioned housing and retained by one closure, a filter structure detachably mounted in 130 the second mentioned housing and retained by the other closure, each structure being independently removable following closure removal and without dismantling the structure, means cooperating with the first mentioned means for 135 securing shaft rotation, and means carried by one of said closures and supporting the last mentioned means.

2. A pump assembly including a rotor housing, an apertured detachable cover therefor, a pump 145 shaft extending through the cover aperture and having an end terminating and seatable in the housing, a unitary filter and relief valve housing arranged to communicate with the rotor housing when assembled, means on the extended end 150 of said shaft for rotating the same, means detachably securing the housings together, a pair of closures for the second mentioned housing, a relief valve structure detachably mounted in the second mentioned housing and retained by the other closure, each structure being independently removable following closure removal and without dismantling the structure, means cooperating with the first mentioned means for securing shaft rotation, and means carried by one of said closures and supporting the last mentioned means.

of said shaft for rotating the same, means detachably securing the housings together, a pair of closures for the second mentioned housing, a relief valve structure detachably mounted in 5 the second mentioned housing and retained by one closure, a filter structure detachably mounted in the second mentioned housing and retained by the other closure, each structure being independently removable following closure removal 10 and without dismantling the structure, one of said closures including an outwardly directed exposed spindle forming portion, and pump shaft rotating means detachably mounted upon the spindle forming portion.

15 3. In a pump assembly, the combination of a rotor housing, a pump shaft extending there-

from, a pulley construction mounted on said shaft and including a threaded portion, a pinion threadedly mounted on the threaded portion of the pulley construction, a unitary filter and relief valve housing arranged to communicate with the rotor housing when assembled, a relief valve structure therein, a filter structure therein, said second mentioned housing including an aperture for each structure and from each of which access may be had to the associated structure, a closure for each aperture, one closure including an extended bearing, a gear on said extended bearing and meshing with said pinion for pump rotation, and a crank for rotating said gear.
